MOSES E. CHENEY, OF LA CROSSE, WISCONSIN, ASSIGNOR, BY MESNE ASSIGNMENTS, TO MOTO METER GAUGE & EQUIPMENT CORPORATION, OF LONG ISLAND CITY, NEW YORK, A CORPORATION OF DELAWARE

RHEOSTAT TANK FITTING ASSEMBLY

Application filed April 11, 1929. Serial No. 354,374.

This invention relates to improvements in rheostat tank fittings for electric indicating instruments, particularly those suitable for use with gasoline tanks applied to motor cars. 5 An important characteristic of this improvement is that it is a unitary tank fitting easily assembled and one that reduces to a minimum the binding of the shaft to which the rheostat arm is attached. It also permits 10 a limited amount of gasoline to pass into the housing or cap of the rheostat to act as a lubricant, which eliminates any tendency of the movable contact button sticking to the rheostat strip or other parts becoming sticky. 15 In particular, it dispenses with any seal between the cap and the gasoline tank, and by reason of the reduction in the number of bearings for the shaft and the simplified arrangement of parts presents a construction 20 in which the bearings for the shaft can be readily reamed in alignment, thereby insuring that the shaft will not bind. In this construction a bushing is employed which has a loose fit with the shaft of such character as 25 to permit gasoline to seep into the cap, and this bushing is elongated sufficiently to make a desirable form of bearing and also to regulate the amount of gasoline that can pass through it to the rheostat cap. 30 Other objects and advantages will be in part indicated in the following description and in part rendered apparent therefrom in connection with the annexed drawings.

To enable others skilled in the art so fully 35 to apprehend the underlying features hereof that they may embody the same in the various ways contemplated by this invention, drawings depicting a preferred typical construction have been annexed as a part of this 40 disclosure and, in such drawings, like characters of reference denote corresponding parts throughout all the views, of which:—

In the drawings Figure 1 is an elevation of the tank fitting; Fig. 2 is a side elevation 45 thereof; Fig. 3 is an enlarged portion of the fitting more clearly showing the sealless elongated bushing.

Referring to Fig. 2 the float arm which projects into the gasoline tank is marked 1 and 50 it has a beveled gear 2 secured to the free end

which is pivotally mounted on the shaft 3 supported by the bracket 4. This bracket 4 is secured to the circular supporting plate 5, and has a cross arm 6 on which is reamed a bearing for the lower end of the rheostat shaft 7. This shaft 7 projects up through the circular supporting plate 5 into the cap or housing 8 for the rheostat and to the upper end of said shaft 7 is securely mounted the rheostat arm 9.

A bushing 10 is secured to the combined bracket 4 and circular plate 5 and this bushing is for that reason preferably shown as having an upper reduced end which projects above the circular plate 5 and by means of a punch, metal from said bushing is forced against the upper surface of the plate 5 thereby clamping the bushing in position with its shoulder 11 against the bottom of the plate 5 or the bracket 4. The shaft 7 is inserted through the bushing before the arm 9 is secured thereto, and a loose fit is formed between the shaft and the inner bore of the bushing. Preferably the parts fit reasonably close, say 2 to 3 thousandths of an inch. 55 By reason of this extended bearing, forming such a fit with the shaft of the character specified, the gasoline is permitted to pass through the bearing in a sufficiently limited amount to act as a lubricant for the parts within the cap 8. It has been found that in this way the arm can be prevented from sticking to the button and yet all danger of explosions or fire is avoided.

From the foregoing description it is apparent that applicant's sealless electric tank fitting is one in which the two bearings can be reamed in sufficient alignment to obviate the objectionable binding of the shaft within its bearings. By dispensing with one of the bearings heretofore employed and employing a bushing of the character heretofore described not only can the two bearings be reamed readily and properly, but the parts can be readily assembled and the necessary 90 amount of gasoline permitted to splash through the upper bearing into the rheostat cap.

The fitting is preferably connected up to a one wire circuit, the tank being grounded and 100

the cap having a terminal (see Fig. 3) which consists of a stud 13, a fiber gasket 14 and insulating and lock washers.

Without further analysis, the foregoing will so fully reveal the gist of this invention that others can, by applying current knowledge, readily adapt it for various utilizations by retaining one or more of the features that, from the standpoint of the prior art, fairly 10 constitute essential characteristics of either the generic or specific aspects of this invention and, therefore, such adaptations should be, and are intended to be, comprehended within the meaning and range of equivalency 15 of the following claims.

Having thus revealed this invention, I claim as new and desire to secure the following combinations and elements, or equivalents thereof, by Letters Patent of United States:—

20 1. In a gasoline tank fitting the combination of a rheostat cap having a chamber therein with a bracket projecting below said cap having unenclosed sides, a rotatable shaft journaled in a bearing positioned in the lower 25 part of said bracket, a float member also journaled in said bracket, an elongated bushing projecting into said chamber and secured adjacent the upper part of said bracket having a lax fit with said shaft, said upper and 30 lower bearings constituting the sole supports for said shaft whereby a limited amount of gasoline can enter said rheostat chamber from said float chamber.

2. In a tank fitting for a receptacle containing an explosive liquid the combination of a rheostat cap forming a chamber with a bracket projecting from said cap, a rotatable shaft journaled in a bearing positioned in the lower part of said bracket, an upper 40 elongated bushing extending into said receptacle and secured to the top of the tank, said shaft having an exposed area intermediate said bearings, the upper elongated bearing having a working fit with said shaft forming

45 a reduced passage extending from said receptacle to said chamber whereby a limited amount of explosive liquid can pass from the exposed area of said shaft through said elongated bearing to said rheostat chamber.

50 3. The combination of a receptacle containing a volatile explosive fluid with a rheostat chamber adjacent said receptacle and subject to the vapors from said volatile fluid; a movable member within said chamber, a connecting member extending from the rheostat chamber into said receptacle, a float operated member controlled by the buoyancy of the fluid, an elongated bearing for the connecting member having a loose fit with said connecting member, forming an attenuated passage for permitting a limited amount of said explosive fluid to pass to said chamber for lubricating the parts in said chamber, a part of 55 said connecting member having an exposed

area extending towards the entrance to said passage.

4. The combination of a receptacle containing a volatile explosive fluid with a rheostat chamber adjacent said receptacle and subject to the vapors from said volatile fluid; a wiper in said chamber; a float-operated member extending from the receptacle into said rheostat chamber and actuating said wiper, said member being controlled by the 70 buoyancy of the fluid; and an elongated bearing for the float-operated member having a loose fit with said member forming a passage for permitting a limited amount of said explosive fluid to pass to said chamber for lubricating the parts in said chamber.

5. The combination of a receptacle containing a volatile explosive fluid with a rheostat chamber adjacent said receptacle and subject to the vapors from said volatile fluid; a wiper in said chamber; a float-operated member extending from the receptacle into said rheostat chamber and actuating said wiper, said member being controlled by the 85 buoyancy of the fluid; and a bearing for the float-operated member having a loose fit with said member forming a passage for permitting a limited amount of said explosive fluid to pass to said chamber for lubricating the parts in said chamber.

6. The combination of a gasoline tank with a rheostat chamber adjacent said tank and subject to the vapors from gasoline in said tank; a wiper in said chamber; a float-operated member extending from the tank into said rheostat chamber and actuating said wiper; said member being controlled by the buoyancy of the gasoline in said tank; and a plain bearing for said member permitting seepage of gasoline between said bearing and member, said bearing being supported by a 90 wall of said rheostat chamber.

In witness whereof, I have hereunto subscribed my name.
